(No Model.)

B. ROBERTS.
SMOKE CONSUMING FURNACE.

No. 501,163.

Patented July 11, 1893.

Thompson Bell

UNITED STATES PATENT OFFICE.

BENJAMIN ROBERTS, OF INDIANAPOLIS, INDIANA.

SMOKE-CONSUMING FURNACE.

SPECIFICATION forming part of Letters Patent No. 501,163, dated July 11, 1893.

Application filed September 13, 1892. Serial No. 445,757. (No model.)

To all whom it may concern:

Be it known that I, BENJAMIN ROBERTS, a citizen of the United States, residing at Indianapolis, in the county of Marion and State 5 of Indiana, have invented new and useful Improvements in Smoke-Consuming Furnaces, of which the following is a specification.

My invention relates to a new and improved furnace for steam boilers the process of consuming the smoke or unconsumed products of combustion therein and the means employed in connection therewith for consuming said products of combustion escaping from the fuel of the main furnace; and its object is to 15 economize the use of the fuel and to prevent the formation of smoke, to prevent the escape of the unconsumed products of combustion, and to create a more perfect rate of combustion to increase the heating efficiency of the 20 furnace. I attain these objects by means of the arrangement of furnace shown in the accompanying drawings and illustrating my invention, and in which similar numbers of reference designate like parts throughout the 25 several views.

Figure 1. is a longitudinal sectional elevation of a boiler furnace showing its arrangement for consuming smoke or other products of combustion. Fig. 2 is a sectional plan view 30 of the same through the line A—B see Fig. 1. Fig. 3. is a transverse sectional elevation of the same through the lines C—D see Figs. 1. and 2. and, Fig. 4. is an enlarged sectional detail view of the nozzle for atomizing the fluid fuel.

The furnace consists of the front wall 1. the fire grate 2. the bridge wall 3. the rear or back uptake wall 4. the intercepting wall 5. intermediate or nearly so between the bridge wall 3. 40 and the rear wall 4. and the side walls 6. which support the boiler 7. A suitable pipe 8. is connected to the dome 9. or any point above the water line of the boiler or it may be connected to another steam pipe having connection with the boiler, and has its opposite end secured to the atomizing nozzle 9. and extends axially with and into the interior of said nozzle with its discharging end at the proper distance from the mouth of the atomizing or reduced end 45 10. thereof, which position is found by experiment and depends largely on the fluidity and viscosity of the fuel used and the pressure and

volume of the steam from the boiler. The fuel, when crude oil or petroleum is used in connection with the atomizer, is conducted 55 from any suitable tank 11 wherein it is stored by a suitable conveying or feed pipe 12. connected to said tank and to the periphery of the nozzle 9. to introduce the fluid into the interior chamber thereof and to surround and 60 to completely cover said steam pipe 8. the heat of which increases the fluidity of the fluid fuel and accelerates the process of atomization.

13. and 14. are suitable stop valves for regulating the supply of the fuel and the flow of 65 steam from the boiler to the atomizing nozzle 9. and 15. 16. are suitable check valves which are intended to shut off a counter pressure against the flow of the steam or fluid fuel.

17. designates the smoke consuming burner 70 which is provided with the inlet or injection opening 18. and the outlet openings or perforations 19. and is supported horizontally and in front of the intercepting wall 5. and directly under the crown or forwardly projecting ledge 20. thereof for the purpose of 75 protecting it from the cutting action of the intense heat generating in the combustion chamber. The opening or mouth 19. of the burner 17. is projected slightly beyond the 80 side wall of the furnace and the reduced or coned end 10. of the nozzle 9. is set to slightly project therein a distance that will form an annular air space between the outer periphery of said coned nozzle 10. of the atomizer 85 and the interior of the mouth 18. of the burner 17. to permit the free flow of the requisite amount of air sufficient to insure a maximum rate of combustion of the atomized fuel as it is ejected from the openings 19. of the burner 90 to produce a fierce heat in the combustion chamber 21. to completely consume all gases escaping from the fuel in the furnace.

The process of perfecting the combustion of the gases escaping from the fuel in the furnace is accomplished by the formation of a 95 concentrated flame in the combustion chamber 21. to the rear of the bridge wall of the furnace and in a position, to directly contact with the escaping gases, to raise their temperature, and to consume them which process is thoroughly accomplished by means of the apparatus described.

To put the apparatus in operation the valves

13. and 14. are first opened to permit the flow of the steam and the fuel oil to enter the atomizer 9, at the contracted or coned end 10 of which said fuel is atomized by the jet of
5 steam issuing from the mouth of the steam supply pipe 8. and is injected into the burner 17. wherein the finely divided particles of the fuel are comingled with the proper amount of atmospheric air to support a high rate of combustion. The atomized fuel which is now rendered highly combustible by reason of its admixture with the atmospheric air issues with a high velocity in jets, from the numerous perforations 19. formed in the burner 17. and
10 in a direction contrary to that of the flow of the escaping gases from the furnace, which produces an eddy in the combustion chamber, as shown by the arrows, thereby thoroughly igniting them in said chamber and raising the
15 temperature of the incombustible gases which impart their heat to the interior surface of the boiler tubes through which they pass on their way to the stack where they are carried to the atmosphere.
20 25 Having thus described the nature and operation of my invention, what I claim as new and useful, and desire to cover by Letters Patent of the United States therefor, is—
1. In a smoke consuming furnace, the combination with the main furnace thereof having a rear bridge-wall of an intercepting wall
30 to the rear of said bridge-wall and forming a combustion chamber, an auxiliary fluid fuel burner horizontally supported in front and
35 near the top of said rear intercepting wall, suitable atomizing apparatus connected to

said burner, and means as described for supplying the fuel and steam to said atomizing apparatus, substantially as and for the purpose set forth.

40

2. In a smoke consuming furnace, the combination with the main furnace, thereof having a rear bridge wall, of an intercepting vertical wall having a forwardly inclined crown, said wall to the rear of said bridge wall, and forming a combustion chamber therewith, a suitable fluid fuel burner within said chamber, and a suitable atomizing nozzle connected to the end of said burner, and means for supplying the atomizing steam and fluid fuel to said nozzle, substantially as and for the purpose set forth.

45

3. In a smoke consuming furnace, the combination with the main furnace thereof having a rear bridge wall, of an intercepting wall having a forwardly inclined crown, said wall to the rear of said bridge wall and forming a combustion chamber therewith, a suitable fluid fuel burner within said chamber, and a suitable atomizing nozzle connected to the end of said burner, and means for supplying the atomizing steam and fluid fuel to said nozzle, substantially as and for the purpose set forth.

50

In testimony whereof I have hereunto set 65 my hand in the presence of two subscribing witnesses.

BENJAMIN ROBERTS.
